UNITED STATES PATENT OFFICE.

HANS MÜLLER, OF DIETIKON, SWITZERLAND.

WARP STOP MOTION.

Application filed May 23, 1922. Serial No. 563,002.

To all whom it may concern:

Be it known that I, HANS MÜLLER, a citizen of the Swiss Confederation, and residing at Dietikon, Switzerland, have invented a certain new and useful Improvement in Warp Stop Motion.

My invention relates to devices in looms and warping machines for indicating the rupture of warp threads, and its object is to provide an improved device which shall be simple to construct and reliable in operation.

According to the invention rows of prongs mounted to swing in their longitudinal direction, are disposed transversely of the warp threads to be controlled and cooperate each with a signalling device, and movable carriers for ruptured warp threads are arranged on both sides of the rows of prongs, which carriers are reciprocated parallel to the longitudinal direction of the prongs so that that row of prongs with which a broken warp thread contacts is caused to oscillate and the allotted signal device is actuated.

Preferably, the rows of prongs are arranged each on a lever having two laterally projecting arms, in the path of each of which is situated a movable tongue that constitutes a point of support for a contact-lever and releases the same when the tongue is moved by its allotted arm, so that the contact-lever can close an electric circuit containing the said signal device.

Conveniently, the movable tongue is mounted to swing about an horizontal axis and, when horizontal, holds the contact-lever in a slanting position there being located within reach of the contact-lever a fixed contact-piece with which the contact-lever automatically contacts when it is released by the tongue under which engages an arm of the swinging lever provided with prongs.

The said movable tongue may bear on a lateral lug of the contact-lever and hold it by means of a downwardly directed nose in an inclined position in which the contact-lever does not make contact with the fixed contact-piece, the arrangement being such that when the tongue is lifted by an arm of the lever carrying the prongs, the nose of the tongue is moved away from the lug of the contact-lever and the latter can swing under the action of gravity against the fixed contact-piece.

In order to increase the inertia of the

levers provided with prongs when they are set in oscillation by a broken warp thread, they may carry each a weight.

Further, the surface of the two carriers arranged to be contacted by the broken warp threads is preferably roughened, and may be constituted by rows of teeth.

The invention consists in the construction, arrangement and combination of parts described hereinafter and pointed out in the claims.

One illustrative embodiment and a modification thereof are illustrated by way of example in the accompanying drawing wherein:

Figure 1 is a side elevation showing one form of mechanism according to the invention, some parts thereof having been removed,

Figure 2 is a top plan view thereof, and

Figure 3 is a cross-section taken on the line III—III in Figure 1;

Figure 4 is a detail view showing a modified form of part of the device shown in Figures 1 to 3, and

Figures 5 and 6 are cross-sectional elevation and side elevation, respectively, showing a modified form of mechanism according to the invention.

Like reference numerals designate like parts throughout the several views.

According to Figures 1 to 3, the device comprises two parallel iron U-beams 1 and 2 mounted at their ends on the frame, not shown, of a loom and disposed transversely below the warp threads 3. Spindles 4 having pointed ends and arranged transversely of the beams 1 and 2 are journaled in bearings 5 between the latter. The spindles carry each a two-arm lever 6 loaded at its lower end by a weight 7 and thereby normally held vertical. At its upper end each lever 6 is provided with a cross-piece 8 having at its upper edge a row of upwardly directed prongs or teeth 9. Further, each lever 6 has two lateral arms 10 and 10^a bent towards the beam 1, which extend each under a tongue 11 and 11^a, respectively, of electrically insulating material. These tongues 11, 11^a are mounted in pairs in bearings 12, one bearing for each pair, which bearings have each a vertical key-hole shaped slot 13 wherein lateral pivot pins 14 of the tongues are readily removably journaled. The tongues 11, 11^a can be readily re-

70

moved as the inside width of each slot 13 is somewhat larger than the thickness of the tongues.

On the inner side wall of the beam 1 two contact-levers 15 are freely rotatably mounted each on a fixed axle 16 between two spindles 4. These contact-levers 15 cross one another and lie slantwise. The upper arms of the levers 15 are made heavier than the lower so that they overbalance the latter and consequently tend to turn causing the lower ends to swing upwards and lie each against the downwardly bevelled free end of a contact-arm 17 that extends below the beam 1. This arm 17 is mounted on a support 18 of insulating material secured to the outside of the beam 1.

The bearings 12 and electric lamps 19 are carried by the support 18. The lampholders 20 are electrically connected by conductors 21 with the axles 16 of the allotted contact-levers 15 at the two sides. The bases 22 of the lamp-holders are connected with a conductor 23 common to them all leading from one pole of an electric battery 24 to whose other pole the contact-arms 17 are connected through the conductor 25. Included in the conductor 25 is an electromagnet 26 whose armature 27 is connected with the stopping device, (not shown) for stopping the loom, so that when the electromagnet is energized the loom is stopped in well known manner.

The lamps 19 are covered by a plate 28 detachably mounted on the support 18. The plate is provided over each lamp with a round hole 29, instead of which a slot may be used if desired.

An axle 30 is journaled on the support 18 below the beam 1; this axle is provided for each two contact-levers 15 with an arm 31 projecting between the latter. Also, one end of the axle 30 carries a lever 32 that is connected with the armature of an electromagnet not shown in the drawing. On starting the loom this electromagnet is temporarily energized and the axle 30 is thereby so rotated that all the arms 31 swing downwards simultaneously and so operate the contact-levers 15 that they rock down away from their allotted contact-arms 17 at their lower ends, whilst their upper ends rock up beyond their allotted tongues 11. When the lever 32 swings back the arms 31 release the contact-levers 15, and in consequence of the greater weight of their upper arms these will bear against the tongues 11 being arrested by the latter in such a position that the lower arms do not contact with the contact-arms 17, so that the above described circuit is not closed and the lamps are not lit.

A carriage which comprises two sheet-metal frames or girders 34 mounted on roller axles 33 at the two sides of the members 8, 9 (only one frame 34 is shown in the drawing) is moved to-and-fro parallel to

the longitudinal direction of the beams 1 and 2 and, consequently parallel to the rows of prongs 9. The reciprocatory motion is brought about by means of a link 35 pivoted to a disk-crank, not shown, driven by the loom. The frames 34 have upwardly bent flanges at their longitudinal edges and are provided with teeth 36. Between these toothed edges is arranged a layer 37 of felt or brushes. In order that the ruptured warp threads shall lie without fail on the layer 37 of felt and in the teeth 36 and, consequently, also in one of the gaps in the rows of prongs 9 a blowing device, not shown, and not constituting part of this invention, is provided in well-known manner above the warp threads.

In the modification shown in Figure 4 the toothed edges of the frames 34 of the carriage are omitted, so that the layers 37 of felt or brushes, e. g. of wire, solely serve as carriers for the fractured warp threads. This modified construction of carriage is particularly adapted for silk looms, as silk threads adhere sufficiently firmly to the rough felt or brushes in order to set a row of prongs in oscillation.

The device described as above operates as follows:—

When a warp thread breaks it is blown by the said blowing device down on to the reciprocating carriage; it will lie transversely of the direction of movement of the latter on the layers 37 of felt and between teeth 36 of the frames 34 and between prongs 9 of the members 8 or between two adjacent levers 6. In consequence of the reciprocatory movement of the carriage the ruptured warp thread 3' (Figure 3) lying on it is moved in relation to the member 8, 9 adjacent thereto so that it abuts against the said member and rocks it. The weight 7 of the lever 6 carrying the member 8 in question turns the lever in consequence of inertia so far that a tongue 11 or 11^a is lifted by one of the laterally projecting arms 10 or 10^a until the upper end of the contact-lever 15 bearing against it loses its support on the tongue and swings downwards. The lower end of the said contact-lever then bears against the allotted contact-arm 17 and closes the circuit including the signal lamp 19 connected to the axle 16 of the contact-lever. The lamp lights up and the loom is simultaneously stopped by the electromagnet 26, 27. The lit signal lamp at once shows where the broken warp thread is situated and facilitates its discovery and seizure. On starting the loom the circuit-closing contact-lever 15 is returned into its normal position by the arm 31 that hits against it.

If a repair of any part of the apparatus is required the reciprocating carriage 34, 37 can at once be removed from the beams 1 and 2, whereupon the entire movable mecha-

nism is exposed and is readily accessible. The movable mechanism with the exception of the members 8, 9 is well protected by the carriage from dirt and dust. The downward beveling of the contact-surfaces of the contact-arms 17 with the contact-levers 15 prevents dust from adhering to them and assures good electrical contact and reliable functioning of the device in this respect.

Referring now to Figures 5 and 6, in this construction of the apparatus the laterally projecting arms 10^b of the lever 6 provided with the member 8 having prongs 9 are arranged below the axis of rotation 4 of the lever and engage under tongues 11^b which are journaled by means of laterally projecting pivots 14^a, similar to the arrangement described above with reference to Figures 1 to 3, but in slanting slots 13^a in the bearing 12^a mounted on the inner side of the beam 1. The tongues 11^b rest each on the upper edge of a laterally projecting lug 15^a of a contact-lever 15^c suspended at 15^b in vertical slots in the bearing 12^a which are wider at the bottom than at the top. These levers 15^c are held by downwardly directed noses 11^c of the tongues 11^b in a slanting position wherein they do not contact with the contact-arms 17^a that project below the beam 1. The signal lamps 19^a let into the support 18^a are electrically connected with the contact-arms 17^a. As in the construction described above with reference to Figures 1 to 3, the signal lamps 19^a are connected with the one pole of an electric battery, not shown, whereof the other pole is connected to the beam 1. In the bearings 12^a which are each U-shaped is journaled the shaft 30^a that carries for each contact-lever 15^c a downwardly directed finger 31^a. On one end of the shaft 30^a is mounted the lever 32^a which is located within the range of a lever 39 constituting the armature of an electromagnet 38, and is so rocked by the same when the electromagnet 38 is energized that the fingers 31^a swing the contact-levers 15^c so far away from the contact-arms 17^a that they lie in front of the noses 11^c. Two stationary rows of prongs 40 or teeth are arranged close beside the outer rows of teeth 36 of the driver or carriage for broken warp threads, which prongs 40 cause a broken warp thread between the rows of prongs or teeth to be pulled even with a small movement of the driver or carriage 33 . . . 37, and cause the levers provided with the prongs 9 to be oscillated with certainty.

This apparatus operates as follows:—

When a lever 6 is set swinging by a broken warp thread as described above with reference to the apparatus shown in Figures 1 to 3, the tongue 11^b situated over one of its arms 10^b is lifted by the latter. The contact-lever 15^c held by the nose 11^c of this

tongue thereby loses its support on the tongue and rocks downwards under the action of gravity until it abuts against the free end of the allotted contact-lever 17^a. The electric circuit which contains the signal lamp connected to the contact-lever 15^c in question is hereby closed so that this lamp lights up. The loom or warping machine is stopped in known manner, for example as described above with reference to Figures 1 to 3. On starting the loom or warping machine the electromagnet 38 is energized, the shaft 30^a having the fingers 31^a is turned so that the latter swing the contact-lever 15^c away from the contact-arms 17^a and the released contact-lever 15^c is returned into its original position.

The construction according to Figures 5 and 6 is simpler than that shown in Figures 1 to 3. The lateral pivots of the contact-levers 15^c and the tongues 11^b can be simply inserted into the downwardly enlarged slots 13^a and 13^b in the bearing 12^a; special spindles passing through the beam 1 for the contact-levers are not required, and the contact-levers themselves are of simpler form. Consequently the manufacture and erection of this construction of apparatus are simpler.

Compared with the well-known mechanisms comprising combs, some of which are mounted to rock and are connected with a device for stopping the loom, which combs are brought alternately into and out of engagement with one another, the above described apparatuses are much simpler and considerably lighter and can therefore be made at a lower cost and can be more rapidly erected.

I claim:—

1. In mechanism for indicating the rupture of warp threads, the combination with a frame, of two movable carriers for ruptured warp threads mounted to reciprocate on said frame in a direction transverse of the longitudinal direction of the warp threads to be controlled and adapted to carry a ruptured thread in the said transverse direction, a row of prongs mounted between said carriers, arranged to move in said transverse direction and adapted to be engaged by a ruptured thread carried by said carriers and be moved thereby, and signalling lamps arranged to be controlled by said row of prongs.

2. In mechanism for indicating the rupture of warp threads, the combination with a frame, of two movable carriers for ruptured warp threads mounted to reciprocate on said frame in a direction transverse of the longitudinal direction of the warp threads to be controlled and adapted to carry a ruptured thread in the said transverse direction, a lever mounted to rock between said carriers in said transverse direction, means

carried by said lever and arranged to be engaged by a ruptured thread carried by said carriers and thereby rock said lever, signalling lamps and means controlled by said lever normally preventing said signalling lamps from giving a signal.

3. In mechanism for indicating the rupture of warp threads, the combination with a frame, of two movable carriers for ruptured warp threads mounted to reciprocate in a direction transverse of the longitudinal direction of the warp threads to be controlled and adapted to carry a ruptured thread in the said transverse direction, a lever mounted to rock between said carriers in said transverse direction, a row of prongs carried by said lever and arranged to be engaged by a ruptured thread carried by said carriers and thereby rock said lever, signalling lamps, a member tending to actuate said signalling lamps, and a stop controlled by said lever normally holding said member in its inoperative position.

4. In mechanism for indicating the rupture of warp threads, the combination with a frame, of two movable carriers for ruptured warp threads mounted to reciprocate on said frame in a direction transverse of the longitudinal direction of the warp threads to be controlled and adapted to carry a ruptured thread in the said transverse direction, a lever mounted to rock between said carriers in said transverse direction, means carried by said lever and arranged to be engaged by a ruptured thread carried by said carrier and thereby rock said lever, electric signalling means comprising a contact-piece and an actuating member tending to contact with the latter and actuate said signalling lamps, and a stop mounted to swing about an horizontal axis and normally coacting with said actuating member and holding the same away from said contact-piece, said lever having an arm arranged to coact with said stop and release the said actuating member when said lever is rocked by a broken warp thread.

5. In mechanism for indicating the rupture of warp threads, the combination with a frame, of two movable carriers for ruptured warp threads mounted to reciprocate on said frame in a direction transverse to the longitudinal direction of the warp threads to be controlled thereby and adapted to carry a ruptured thread in the said transverse direction, a lever mounted to rock between said carriers in said transverse direction, means carried by said lever and arranged to be engaged by a ruptured thread carried by said carriers and thereby rock said lever, electric signalling lamps comprising a fixed contact-piece and a pivoted circuit-closing member tending under gravity to contact with said contact-piece, and a tongue mounted to swing about an horizontal

axis and having a nose arranged to coact with said circuit-closing member and hold the same in its cut-out position, said lever having an arm arranged to rock said tongue and remove said nose from said circuit-closing member when said lever is rocked by a broken warp thread.

6. In mechanism for indicating the rupture of warp threads, the combination with two beams, of two movable carriers for ruptured warp threads mounted to reciprocate on said frame and carry a ruptured thread in a direction transverse of the longitudinal direction of the warp threads, a lever mounted to swing between said carriers in said transverse direction about a horizontal axis and carrying a weight below said axis, means carried by said lever and arranged to be engaged by a ruptured thread carried by said carriers and thereby rock said lever, signalling lamps, and means controlled by said lever normally preventing said signalling lamps from giving a signal.

7. In mechanism for indicating the rupture of warp threads, the combination with a longitudinal support mounted transversely of the warp threads to be controlled, of two movable carriers for ruptured warp threads mounted on said support and arranged to reciprocate along the same, said carriers having each a rough upper surface adapted to engage a ruptured thread and carry the same lengthwise of said support, means mounted between said carriers to move in the same direction and adapted to be engaged by a ruptured thread carried by said carriers and be moved thereby, and signalling lamps arranged to be controlled by said former means.

8. In mechanism for indicating the rupture of warp threads the combination with beams mounted in the transverse direction of the warp threads to be controlled, of two movable carriers for ruptured warp threads arranged to reciprocate along said beams, said carriers having each a rough upper surface and upstanding teeth at each side thereof adapted to engage a ruptured thread and carry the same in said transverse direction, means mounted between said carriers to move in said transverse direction, said means being adapted to be engaged by a ruptured thread carried by said carriers and be moved thereby in said transverse direction, and signalling lamps arranged to be controlled by said former means.

9. In mechanism for indicating the rupture of warp threads, the combination with two parallel beams mounted in the transverse direction of the warp threads to be controlled, of two movable carriers for ruptured warp threads mounted to reciprocate along said beams, said carriers being adapted to engage a ruptured thread and carry the same in said transverse direction, means

mounted between said carriers and adapted to be moved by a carried warp thread in said transverse direction, a support carried by one of said beams, and signalling means comprising a lamp carried by said support arranged to be controlled by said former means.

10. In mechanism for indicating the rupture of warp threads, the combination with two parallel beams mounted in the transverse direction of the warp threads to be controlled, of two movable carriers for ruptured warp threads mounted to reciprocate along said beams, said carriers being adapted to engage a ruptured thread and carry the same in said transverse direction, a plurality of levers each having prongs at its upper end mounted to swing between said carriers, said prongs being adapted to be moved by a carried warp thread and thereby rock said levers, a support carried by one of said beams, signalling means comprising lamps, one for each lever carried by said support arranged to be controlled by said levers, and a plate carried by said support above said lamps, said plate having an aperture above each lamp.

11. In mechanism for indicating the rupture of warp threads, the combination with two parallel beams spaced apart and mount-

ed in the transverse direction of the warp threads to be controlled, of a carriage comprising two carriers mounted to reciprocate along said beams, said carriers having between them a gap extending lengthwise of said beams and having each a roughened upper surface adapted to engage a ruptured thread and carry the same in said transverse direction, a plurality of levers each having prongs at its upper end mounted to swing in said gap between said drivers, said prongs being arranged to be moved by carried warp threads and thereby rock each an allotted lever, a support carried by one of said beams, and signalling means comprising a plurality of sets of lamps, fixed contact-pieces, circuit-closing members, and tongues for holding the latter open, one set for each lever, mounted on one of said beams, each lever having an arm arranged to coact each with one of said tongues and release the same from its allotted circuit-closing member when the lever is rocked by a driven thread.

In testimony whereof, I affix my signature in the presence of two witnesses.

HANS MÜLLER.
